UNITED STATES PATENT OFFICE.

GEORG HOFFMANN, OF HANOVER-HAINHOLZ, GERMANY.

APPARATUS FOR PREPARING OLD AND NEW MOLDING-SAND.

1,036,239.

Specification of Letters Patent. Patented Aug. 20, 1912.

Application filed September 11, 1909, Serial No. 517,239. Renewed July 5, 1912. Serial No. 707,908.

To all whom it may concern:

Be it known that I, GEORG HOFFMANN, subject of the Emperor of Germany, residing at Hanover-Hainholz, in the Province 5 of Hanover, Germany, have invented certain new and useful Improvements in Apparatus for Preparing Old and New Molding-Sand, of which the following is a specification.

This invention relates to an apparatus for preparing molding sand as it is used for foundry purposes.

An object of the invention is to simplify the manufacture of molding sand by combining a plurality of apparatus in one device, 15 these apparatus in the known manufacturing devices having been disposed in various parts of the foundry or molding room.

This required a plurality of conveying contrivances which were adapted to interconnect the various devices.

Another object of the invention is to reduce the number of conveying means interconnecting the various devices to as small a number as possible.

Another object of the invention is to provide a machine which takes less floor space than the various apparatus would occupy if they would be separated from each other.

Another object of the invention is to obtain economical advantages in erecting a new plant for the preparation of molding sand compared with known devices of this kind.

With these and other objects in view one embodiment of the invention is shown in the accompanying drawing and described in the following specification and the claims appended thereto.

In the drawing: Fig. 1 is a longitudinal section; Fig. 2 is a cross section on line A—A of Fig. 1. Fig. 3 is a cross section on line B—B of Fig. 1. Fig. 4 is a section on line C—C of Fig. 1. Fig. 5 is a section on line D—D of Fig. 1.

Molding sand as it is used for foundry purposes usually is composed of a large percentage of silica, metallic-oxids and other ingredients. It is customary to manufacture the sand by mixing certain amount of old and used molding sand with new sand and with coal dust. Old molding sand requires a certain hardness and porosity and these qualities depend upon the sand used on the bottom in which the sand is received

prepared themselves and on the manner in which they are mixed with each other.

The apparatus which forms the subject-matter of this invention comprises therefore in the main a mill for the old sand and a sifting apparatus for the same, similar devices for the new sand, a mixing device for both kinds of sand and a container for coal dust, said last named ingredient being added to the composition.

It is to be understood that in the following one embodiment is described in which the various devices as they are preferably used are specified, but it is obvious for an expert skilled in the art to substitute similar contrivances without going beyond the scope of this invention.

The new sand is supplied to a crushing mill *a* in which a plurality of heavy wheels 10 travel in a circular path in a mixing dish 11 about a preferably vertical axis 12 while these heavy wheels simultaneously rotate about their horizontal shafts 13. A funnel-shaped mouth 14 serves for conveying the new sand to the crushing dish, over which a mandible 14' may be disposed. The crushed sand is discharged from the dish through a chute *a'* and is conveyed from there to a preferably vertical bucket conveyer or similar device *g*. A metal casing 15 incloses the conveyer which receives its drive from the upper shaft 16. An opening 17 may be provided at the foot of the casing so that the interior of the conveyer may be readily accessible for inspection and repair. The buckets 18 convey the crushed new sand 90 upon a screw conveyer 19, which carries the sand into the interior of a conical riddle *b*, the meshes of said riddle being of a certain size. That kind of sand which is fine enough to pass through the meshes of the riddle is 95 conveyed through the chute or hopper *b'* to a screw conveyer *h*. The coarse grain sand which cannot pass through the meshes of the riddle is carried toward one end of the riddle and having arrived at said end it 100 drops into a chute *n*, leading back to the grinding mill *a* in which the treatment of the sand is repeated.

The crushing device for old sand comprises a mill which may be similar to the grinding mill *a* or which as in the embodiment shown in the drawing may comprise a mill *c*. The old sand is supplied to the

rollers 20 through the funnel 21 and after having been crushed between the rollers which may be pressed against each other by the force of a spring 22 it falls on a reciprocating sifter 23. The reciprocating sifter 23 may receive its movement from a pulley 24 under co-action with the crank arm 25 guiding means 26 being provided for reciprocating the sifter in substantially horizontal 10 position. The crushed old sand is discharged from the sifter to the foot of a conveyor 27, preferably disposed vertically and arranged similar to the conveyor 28 described above. This conveyor likewise may be provided with an opening 29 at the foot into which the forward spout 26 of the sifter 23 extends. From the top end of the conveyor 27 a chute 30 (Fig. 2) leads the old crushed sand to a spiral conveyor 31 preferably disposed on a level below the aforementioned spiral conveyor 27 while the new crushed sand passing through the meshes of the middle 32 is conveyed to said last named conveyor 31. The spiral conveyor 31 gradually moves the new crushed sand to the left out thereof from where it drops through a short chute 33 into a channel 34 which encloses the spiral conveyor 31. This conveyor gradually shifts the new sand to the right hand end 35 primarily mixing thereby the two kinds of sand in a thorough way. From the right hand end of the conveyor the mixed sand is discharged into the funnel 28 of another secondary mixing machine 36 which in the embodiment illustrated, comprises two rotary members 29 and 30, disposed in opposition and provided with a plurality of elements projecting toward each other. The sand conveyed between the two rotary members 29 and 30 is engaged by the projecting elements 31, so that a further thorough mixing of the same is obtained before it is discharged from the mixing machine 36.

Coal dust which forms the third important ingredient of the mudding sand is stored in a bin k from which it may drop through a sheet chute k' into a channel or trough 32, which incloses the spiral conveyor h ; as stated before this conveyor 50 serves for leading new crushed sand to the left end and the coal dust coming through chute k' is therefore thoroughly mixed with the crushed new sand.

As clearly indicated in the drawings the
 55 machines to which the raw material must be
 supplied, namely, the grinding mill α , the
 crushing rollers β , and furthermore the ma-
 chine from which the finished sand is dis-
 charged are disposed on the ground floor
 60 The sifting apparatus for the new crushed
 sand and the primary mixing device there-
 ally are arranged above the aforementioned
 devices so that an advantageous compendious
 arrangement is obtained. The platform
 65 surrounded by a railing γ and supported on

the platform as series for accessibility of the upper platform. The conveyor is preferably suspended from said platform. A ladder extends from the ground floor to the platform as shown in Fig. 5.

The operating means for the entire apparatus are advantageously disposed on the upper platform and at the rear of the machine, so as not to interfere with the supply and grinding and operating means for the single devices. In the embodiment shown they comprise a main shaft *m* which by transmission belts or in some other way may be operatively connected with the driving means for the single devices. A shaft *l* provided with pulleys 35 and 36 at one end thereof and with a barrel gear 37 serves for the drive of the grinding mill *a*. The shaft *l* of said grinding mill preferably is provided with a key 38 meshing with the pinion 39, this gearing being advantageously disposed in the support casing 39 of the grinding mill *a*; apertures 40 may be provided in the casing to admit air to the gearing.

shaft 11 supported in suitable bearings 96
on the platform 9 and provided with a pulley 12 is connected to the pulley 42 on the
shaft 4 by means of a belt 41. One end of
the shaft 4 extending beyond the platform
carries a sprocket 13 which in the embodiment
illustrated in the drawing meshes with a
gear 36 rigidly mounted on the shaft 47 of
the spiral conveyer 3. A second pulley 48
supported on the shaft 4 is connected to a
pulley 49 on the shaft 96 by means of a belt
50. From the shaft 96 the riddle 51 is driven
by means of a pulley 51 on the shaft 96 and
a transmission belt 52 leading over a driven
pulley 53 on the shaft 54 of the riddle. The
conveyer 54 is mounted on shaft 54. This
conveyer 54 is connected by means of chain
driving to some other suitable way 55 to a
device 56 which is adapted to regulate the
distribution of the coal dust to the trough 32
for the spiral conveyer 3. This conveyer 100
may be driven as shown in Fig. 2 by means
of a sprocket 57 from a shaft 58 which
last named shaft is driven by a belt 59 run-
ning over the pulley on the shaft 96. The
two conveyers 3 and 54 also may be driven
from the shaft 96 under control of the bevel
gearing 60. A sprocket 61 being provided
in the conveyer 3 and the sprocket shaft be-
ing in gearwise connection with the shaft 16
of the conveyer 54. The grinding mill 62 re-
ceives its drive from the shaft 96 over the
pulleys 63 the shaft of said pulley being pro-
vided with a sprocket 64 which meshes with a
large gear wheel 65 on the shaft of one of
the rollers 66. The compensating movement
of the riddle 51 is obtained from the shaft 96
by means of a belt leading over the pulley
63, the shaft of said pulley being in connec-
tion with the riddle by means of the connect-
ing arm 67. The two rotary members of the
105
110
115
120
125
130

mixing machine finally are driven from the shaft *m* by means of the pulleys 67 and 68 which are connected with the shaft *m* by one straight and one crossed belt respectively as indicated in Fig. 1.

5 A shaft 70 carries a worm 77 which is driven by a belt, not shown, from the pulley 74. The worm gear 77 is engaged with the hob 71 mounted on the shaft 73, and imparting thereby slow rotating movement to the same. The shaft 73 is provided at each end with a transverse member 72, said member being connected with the slides 75 and 75' respectively for closing or opening the inlet 10 and outlet apertures respectively of the casting 14' of the grinding mill. These transverse members are placed on the shaft 73 so that the slide 75 is in closing position when slide 75' is open and vice versa. The object 20 of this arrangement is to prevent the sand thrown through the feeding aperture 14 from leaving the grinding mill before it has undergone the grinding operation.

From the foregoing it will be seen that 25 the raw materials singly conveyed to the machine are discharged therefrom finely crushed and thoroughly mixed with each other. It is also obvious that in the compendious structure of the machine not more than one attendant is required to watch the 30 various devices and operate the same. It is furthermore obvious that the entire drive for the machine is derived from the main shaft *l* which is readily accessible for oiling 35 and which in the embodiment shown may easily be inspected from the ground floor of the machine. It is furthermore obvious that in this structure the necessity of building a plurality of fundaments for several 40 machines is dispensed with and a considerable saving is connected with this feature.

1. claim:—

1. A machine for preparing molding sand comprising in combination, a device for reducing new sand from coarse to fine condition, a device for sifting the fine new sand, a device for crushing and sifting old sand, separate conveying means for the sand from the aforesaid devices respectively, a common 25 conveying means for said sands, a device for intermixing both kinds of sand, said common conveying means leading said sands to said mixing device, common actuating means for said devices and conveying means, 50 and means for adding coal-dust to the sands.

2. A machine for preparing molding sand, comprising in combination, a device for reducing new sand from coarse to fine condition, a device for sifting the fine new sand, a device for crushing and sifting old 60 molding sand, separate means for conveying said sands in vertical direction from said reducing and crushing device respectively, common means for conveying both kinds of sand in horizontal direction, a device for in-

termixing both kinds of sands, said common conveying means leading the sand to the intermixing device, means for adding coal-dust to the sands, and common actuating means for said devices and conveying means. 70

3. A machine for preparing molding sand, comprising in combination, a grinding mill for new sand, a sifting device for ground new sand, a means for conveying ground new sand upwardly to the sifting device, a crushing and sifting mill for old molding sand, means for conveying old molding sand upwardly from said crushing mill, a third conveying means for both kinds of sand in common and for intermixing said sands, a second device for intermixing said sands, said common conveying means leading to said intermixing device, means for adding coal-dust to the mixture, and common actuating means for said devices and 85 conveying means.

4. A machine for preparing molding sand, comprising in combination, a grinding mill for new sand, a sifting device for ground new sand disposed above said mill, means 90 for conveying sand from said mill to said sifting device, a crushing and sifting mill for old molding sand disposed below said sifting device, means for conveying sand from said crushing mill upwardly, a third 95 conveyer, means for leading sand from said second conveying means to said third conveyer, means for leading sand from said sifting device to said third conveyer, an intermixing device for both kinds of sand 100 disposed on a level below said sifting device, said third conveyer leading both kinds of sand toward said mixing device, a device for adding coal-dust to the sands, and actuating means for said devices and conveying 105 means.

5. A machine for preparing molding sand, comprising in combination, a grinding mill for new sand, a device for sifting ground new sand disposed above said mill, means 110 for conveying sand from said mill to said sifting device, means for leading unsifted sand from the sifting device back to the mill, a crushing and sifting mill for old molding sand disposed below said sifting device, 115 means for conveying sand from said crushing mill upwardly, a third conveyer, means for leading sand from said second conveying means to said third conveyer, means for leading sifted sand from said sifting device to said third conveyer, a device for intermixing both kinds of sand disposed on a level below said sifting device, said third conveyer leading both kinds of sand toward 120 said mixing device, a device for adding coal-dust to the sands, and actuating means for said devices and conveying means.

6. A machine for preparing molding sand, comprising in combination a grinding mill for new sand, a sifting device for ground 125

- 4
- new sand disposed above said mill, a means for conveying ground sand from said mill to said sifting device, a crushing and sifting mill for old molding sand in juxtaposition to said grinding mill, means for conveying sand from said crushing mill to a primary mixing and conveying device, means for leading sifted new sand from the sifting device to said mixing and conveying device, said primary mixing and conveying device being disposed at a level above said mills, a secondary mixing device disposed at a level with said mills, means for adding coal-dust to the mixture, and actuating means for said mills and conveyers.
7. A machine for preparing molding sand, comprising in combination a grinding mill for new sand, a sifting device for ground new sand disposed above said mill, a means for conveying ground new sand from said mill to said sifting device, a crushing and sifting mill for old molding sand disposed in close juxtaposition to said grinding mill, a means for conveying sand from said crushing mill upwardly, both of said conveying means being disposed opposite each other, a primary mixing and conveying device disposed at a level above said mills, means for leading crushed old sand from said second conveying means to said primary mixing and conveying device, means for leading sifted new sand from said sifting device to said primary mixing and conveying device, a secondary mixing device, said primary mixing device leading the sand toward said secondary mixing device, means for adding coal-dust to the mixture, and actuating means for said mills, conveyers and devices.
8. A machine for preparing molding sand, comprising in combination, a grinding mill for new sand, a sifting device disposed above said mill, a means for conveying ground new sand from the mill to said sifting device, a chute for leading unsifted sand from said sifting device to said mill, a conveyer disposed below said sifting device, another chute extending from said sifting device to said conveyer, a crushing and sifting mill for old sand disposed in close juxtaposition to said grinding mill, a second conveyer disposed above said mills and below said first named conveyer a third chute leading from said first named conveyer to said second conveyer, a means for conveying old crushed sand from said crushing mill to said second conveyer, said means for conveying new ground sand and old crushed sand being disposed on different sides respectively of the machine and opposite each other, a mixing device disposed at a level with said mills, said second conveyer leading the sand toward said mixing device, a bin containing coal-dust discharging into said second conveyer, and common actuating means for said mills, devices and conveyers.
- In testimony whereof I have hereunto set my hand in presence of two subscribing witnesses.

GEORG HOFFMANN.
